[57] **CLAIM**

The ornamental design for the oak-textured contoured panel, as shown and described.

DESCRIPTION

FIG. 1 is a front elevational view of an oak-textured contoured panel in accordance with the invention, the rear being a mirror image thereof and the broken lines showing the outlines of a door being for illustrative purposes only and forming no part of the claimed design;

FIG. 2 is an enlarged fragmentary front elevational view thereof;

FIG. 3 is an enlarged fragmentary cross-sectional view taken along line 3—3 of FIG. 1; and,

FIG. 4 is an enlarged fragmentary perspective view of the upper right corner of the oak-textured contoured panel shown in FIG. 1.
